(57) **CLAIM**

The ornamental design for a track-type loader, as shown and described.

DESCRIPTION

FIG. 1 is a rear top perspective view of a track-type loader showing our new design;

FIG. 2 is a front elevation view thereof;

FIG. 3 is a right elevation view thereof;

FIG. 4 is a left elevation view thereof;

FIG. 5 is a rear elevation view thereof; and,

FIG. 6 is a top plan view thereof.

The bottom view of the track-type loader is not visible during ordinary use and forms no part of the claimed design.
